(57) **CLAIM**

The ornamental design of a battery, as shown and described.

DESCRIPTION

FIG. 1 is a perspective view of a battery showing our design. FIG. 2 is a front elevational view of the battery of FIG. 1. FIG. 3 is a rear elevational view of the battery of FIG. 1. FIG. 4 is a left-side elevational view of the battery of FIG. 1.

FIG. 5 is a right-side elevational view of the battery of FIG. 1.

FIG. 6 is a top plan view of the battery of FIG. 1; and, FIG. 7 is a bottom plan view of the battery of FIG. 1. Broken lines are for illustrative purposes only and form no part of the claimed design.
